US00D540317S

(12) **United States Design Patent** (10) Patent No.: **US D540,317 S**
Nakajima (45) Date of Patent: **** Apr. 10, 2007**

(54) **PORTION OF A HANDSET**

(75) Inventor: **Shiho Nakajima**, Tokyo (JP)
(73) Assignee: **Nokia Corporation**, Espoo (FI)
(**) Term: **14 Years**

(21) Appl. No.: **29/245,289**(22) Filed: **Dec. 22, 2005****Related U.S. Application Data**

(62) Division of application No. 29/210,064, filed on Jul. 27, 2004, now Pat. No. Des. 518,459.

(30) **Foreign Application Priority Data**

Mar. 12, 2004 (FI) M20040041

Primary Examiner—Jeffrey Asch(74) *Attorney, Agent, or Firm*—Banner & Witcoff, Ltd.(57) **CLAIM**

The ornamental design for a portion of a handset, as shown and described.

DESCRIPTION

FIG. 1 is a bottom plan view of a handset showing my new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof; and,

FIG. 8 is a perspective rear view thereof.

The broken line showing of the remainder of the handset is for illustrative purposes only and forms no part of the claimed design.
